DESIGN FOR A VACUUM CONTROL VALVE FOR MILKING MACHINES

Harry De Laere, Lansing, Mich.

Application February 24, 1940, Serial No. 90,491

Term of patent 3½ years

To all whom it may concern:

Be it known that I, Harry De Laere, a citizen of the United States, residing at Lansing, in the county of Ingham and State of Michigan, post-office address No. 310 South Hosmer Street in the said city, have invented a new, original, and ornamental Design for Vacuum Control Valves for Milking Machines, of which the following is a specification, reference being had to the accompanying drawing, forming part thereof.

In the drawing:

Fig. 1 is a front elevational view of a vacuum control valve, for milking machines, showing my new design; and

Fig. 2 is a side elevational view thereof.

Fig. 3 is a side elevational view of Fig. 2.

I claim:

The ornamental design for a vacuum control valve for milking machines, as shown.

HARRY DE LAERE.
